UNITED STATES PATENT OFFICE.

GEORGE W. WILSON, OF LANESBOROUGH, MINNESOTA, ASSIGNOR TO HIMSELF, HELMER C. SCHELBERG, AND OSCAR J. WALL, ALL OF SAME PLACE.

CAR-COUPLING.

SPECIFICATION forming part of Letters Patent No. 367,944, dated August 9, 1887.

Application filed March 21, 1887. Serial No. 231,691. (No model.)

To all whom it may concern:

Be it known that I, GEORGE W. WILSON, of Lanesborough, in the county of Fillmore and State of Minnesota, have invented a new and 5 Improved Car-Coupling, of which the following is a full, clear, and exact description.

My invention relates to car-couplings, and has for its object to provide a simple inexpensive coupling by which cars may be coupled 10 automatically as they come together, and without requiring the train-men to stand between the cars and expose themselves to injury.

The invention consists in certain novel features of construction and combinations of parts 15 of the car-coupling, all as hereinafter fully described and claimed.

Reference is to be had to the accompanying drawings, forming a part of this specification, in which similar letters of reference indicate 20 corresponding parts in all the figures.

Figure 1 is a vertical sectional elevation of the end parts of two cars provided with the improved couplings, and indicates the positions of the parts as the coupling is about to be effected. Fig. 2 is a sectional view of one draw-head, illustrating the action of the coupling-link holding-block or adjuster. Fig. 3 is a plan view of the draw-head and coupling-link. Fig. 4 is a plan view in horizontal section on 25 the line $x-x$, Fig. 2. Fig. 5 is a front view of the draw-head with the coupling-link in section, and Fig. 6 is a perspective view of the coupling-pin.

The draw-head A is provided with a socket, 35 B, in which the coupling-pin C, link D, and link holder or adjuster E operate, as presently described. The coupling-pin passes through a hole or slot, F, in the top of the draw-head, and into or through a hole or slot, G, in the 40 bottom of the draw-head. The floor of the socket B slopes or is rounded outward and downward at b from a point, b' , back of which the floor of the socket stands about level to allow the back end of the link-adjusting block 45 E to rest fairly on it when the link is not in the draw-head, and, as indicated by the dotted lines in Fig. 2 of the drawings, while the upturned front lower surface, e , of the block E is directly above the sloping surface b of the

link-socket floor, a flaring opening thus being 50 provided between the faces b and e for the entrance of the link D, which in passing fully into the socket B lifts the outer end of the block E, which bears onto the upper surface of the link, the upper surface of the block E 55 then rising to or toward the upper flaring wall or roof of the link-socket. The block E is held in the socket B by a pin, H, which passes through a vertically-ranging hole in the draw-head and through an aperture, e' , in the block, 60 and is too far back to be struck and injured by the link when the faces of opposing draw-heads meet in coupling the cars. The block E is provided with a slot, e'' , (see Fig. 4,) giving room for the passage of the coupling-pin 65 C through it. By pushing the coupling-link into the draw-head of one car more or less the block E will support the link in true horizontal position, or at a greater or less incline therefrom, and hold the link so that its outer 70 end will stand at proper height to enter the draw-head socket of an opposing car, the link being held where set by the gravity of the block. The link may thus be adjusted higher or lower at its outer end by simply forcing it 75 in more or less beneath the block E, and the link need not be otherwise held, hence the train-men are not required to go between the cars to hold up the link while coupling the cars.

80 The coupling-pin C has a peculiar form, on which much of the efficiency of this invention depends.

The head I of the coupling-pin has or may have a lug perforated at i for connection of a 85 chain or cord (not shown) leading to the top of the car for raising the pin therefrom for uncoupling, and at the base of the head side shoulders, J, are provided to limit the fall of the pin by contact with the top of the draw-head. The back edge of the pin from the shoulders J downward to near the point of the pin is concaved lengthwise at K, and the rear lower part, L, of the pin is rounded over forward to cause it to easily slide up the inclined 90 face or back wall, g , of the lower pin-slot, G. From its extremity or point M the front edge 95 of the coupling-pin ranges upward and out-

ward in a comparatively-straight line at N to an elbow or boss, O, which projects quite a little from a line drawn through the center of the pin-head and the point of the pin, and 5 from the elbow O the front edge of the pin is curved gradually backward and upward at P to the pin-head I.

A lug, R, formed on top of the draw-head at its front, is preferably cut away at the rear 10 face to form a guide to the parts P O of the coupling-pin as it is lifted, and a lower projection or guide-lug, S, is preferably formed on top of the draw-head behind the pin-hole F thereof. The coupling-pin is rounded over 15 at its front and rear edges and tapers flatwise or sidewise a little toward its point M, which is preferably rounded laterally to facilitate entrance of the pin into the lower hole, G, of the draw-head. The body of the pin is made narrow 20 or flat from side to side and fits the sides of the upper hole, F, loosely, but so as to prevent the bodily turning of the pin in the draw-head and always hold its projection or elbow O and overhanging front edge, N, toward the 25 front of the link-socket.

The operation is as follows: The inner end of the coupling-link D, held by the pin C of one draw-head, will be set beneath the block E to hold its outer end at the required height 30 to enter the opposing draw-head—say the left-hand one in Fig. 1 of the drawings—and as the link enters between the curved faces b c of the link socket B and block E and strikes the front edge, N, of the pin C of said left-hand 35 coupling said pin will be forced against the inclined rear wall, g, of the lower pin-hole, G, and the pin will be lifted quite easily, the concaved rear edge, K, of the pin allowing it to be forced backward by contact of the parts P O 40 of the pin with the front end of the upper pin-hole, F, and the lug R. The overhanging front edge, N, of the pin facilitates the lifting of the pin by the link. As the end of the link passes under and behind the point M of the 45 pin C, the pin will fall through the link and couple the cars. As the coupling-pin rises and falls, the lugs R S on the draw-head prevent excessive forward and backward rocking of the point of the pin to facilitate its safe entrance 50 into the lower hole, G, of the draw-head. To uncouple the cars, it is only necessary to withdraw either one of the coupling-pins until the link may escape the point of the pin as the cars are drawn apart.

55 It will be seen that when the coupling-pin is fully down its concaved rear edge, K, gives a good draft-hold for the link, and the projection or elbow O at the front of the pin then stands out below and in front of the forward

end of the pin-hole F, thereby preventing the pin from jumping upward out of the link when the draft is applied to the cars.

The draw-head may be cast cheaply in one piece, and the pin will preferably be made of cast or wrought steel, and the link may be of the ordinary form. The coupling has very few and no delicate parts—such as springs—and the action in coupling is entirely automatic and does not require the train-men to stand between the cars and expose themselves to injury.

Having thus fully described my invention, what I claim as new, and desire to secure by Letters Patent, is—

1. In a car-coupling, the combination, with 75 the draw-head having a link-socket, B, formed with the sloping front-floor portion, b, and having a vertical pin, H, at its inner end, of a link holding and adjusting block, E, having a vertical aperture in its inner end of greater 80 diameter than the said pin to allow the said inner end to move vertically on the pin, and having a curved lower front face, e, opposite face b of the link-socket, substantially as set forth.

2. A car-coupling comprising the draw-head A, provided with the link-socket B b, the upper opening, F, the lower opening, G, having the inclined rear wall, g, the vertical pin H at the inner end of the socket, vertically-slotted 90 block E, having an enlarged aperture at its inner end, through which pin H passes to allow the block vertical movement thereon, and the coupling-pin I, having the concave rear edge terminating in the rounded lower portion, L, 95 and the overhanging forward edge, N, substantially as set forth.

3. The coupling-pin I, having the supporting-shoulders J J, the concave rear edge, K, the lower rounded rear edge, L, the overhanging forward edge, N, the upper receding front edge portion, P, and the intermediate elbow, O, substantially as set forth.

4. In a car-coupling, the draw-head A, provided with a link-socket, B, coupling-pin 105 holes F G, said hole G having an inclined rear wall, g, in combination with a coupling-pin, C, formed with an overhanging front edge portion, N, and receding upper front edge portion, P, forming a projection or elbow, O, at the 110 front of the pin, and said pin also having a concaved upper rear edge portion, K, and lower rounded rear edge portion, L, substantially as herein set forth.

GEORGE W. WILSON.
